ELECTRIC HAND LAMP

Fredrick J. Kirkman, Freeport, Ill., assignor to Servel, Inc., Evansville, Ind., a corporation of Delaware

Filed Jan. 7, 1960, Ser. No. 1,044

6 Claims. (Cl. 240—10.63)

This invention relates to electric hand lamps and more particularly a multicell lamp using a plurality of separate batteries of, for example, the flashlight type, and aims to provide an improved and simplified structure of this type.

In an important aspect, the present invention contemplates, as here shown, a separable two-part structure that embodies a battery receptacle and an offset frame, the latter including a cover part for the receptacle while at the same time providing a handle for the lamp and carrying terminals making electrical contacts with the batteries in the receptacle by a sliding interconnection of the cover with the receptacle. A contact assembly in the bottom of the battery receptacle is removable for cleaning, repair or replacement in the event of damage due, for example, to cell leakage. The frame also carries a pivotally mounted lamp head and switch parts including a switch button.

The advantages of the invention will be apparent from the following description, taken together with the accompanying drawings, showing an illustrative embodiment of the invention.

In the drawings—

FIG. 1 is a side elevational view of the lamp;

FIG. 2 is a front view thereof;

FIG. 3 is a view of the frame separated from the battery receptacle;

FIG. 4 is a view of the under-face of the frame shown in FIG. 3;

FIG. 5 is a fragmentary end view thereof;

FIG. 6 is a view of the upper end of the battery receptacle broken away to save space and for descriptive purposes:

FIG. 7 is a plan view of the battery receptacle looking into its interior, the position of the batteries being indicated in dotted lines;

FIG. 8 is a fragmentary end view of parts shown in FIGS. 6 and 7; and

FIG. 9 is an enlarged elevational sectional view of the lamp, as shown in FIG. 1, broken away to conserve space.

Referring in detail to the illustrative construction shown in the drawings, numeral 11 indicates a metal receptacle for the batteries (cells) for the lamp. The receptacle, as best seen in FIG. 9, is elongated to receive a plurality of dry cells of, for example, the ordinary flashlight type. Three dry cells 12, 13 and 14 are here aligned in a row longitudinally of the can and are placed in electrical series by having the end cells 12 and 14 upright and the middle cell 13 inverted.

Spring contact members for the cells are arranged in the bottom of the receptacle 11 on a laminated insulating base pad 15. As here shown, at one end of the spring contact 16, which is riveted to the base pad 15 at 17, makes contact by its spring tongue 16a with the negative terminal 14a of the cell 14 at 18, and, by its tail end 16b, makes a ground contact at 19 with a portion 20 of the battery receptacle. As shown in the example, this connection is advantageously made with the rib-like overlapping portion of the sheet metal of the receptacle. Spring contact 21 at the other end of the receptacle is riveted to the base pad 15 at 22 and 23 and is an elongated double contact having its opposite ends forming spring tongues 24 and 25. Spring tongue 24 at 26 engages the positive central terminal 13a of in-

2

verted cell 13, and spring tongue 25 at 27 engages the negative can terminal 12a of cell 12. Thus, terminals 12a and 13a are electrically connected.

It will be noted from FIG. 9 that the pad 15 assembly 5 in the bottom of the battery receptacle is not permanently fastened in place by fixed means but is, rather, securely held in its proper position by means of the tail 16b of conductor strip 16 acting as a latch. This arrangement provides a very convenient and therefore inexpensive means for assembling the receptacle, the pad sub- 10 assembly merely being pressed down into position. As this is done, the end 16b of the conductor strip scrapes and tightly engages the inner surface of the metal receptacle with a continuing pressure to insure a reliable 15 electrical contact. For greater assurance against unintended lifting of this pad, dimples 11a may be impressed inwardly near the bottom of the receptacle to serve as additional retaining means for the pad.

The frame is indicated generally by the numeral 28. 20 At its top where it is open and adapted to interengage with the frame, the receptacle 11 along its longitudinal edges has a pair of outwardly directed flanges 29 that are conveniently formed integrally with the side members of the receptacle respectively, and at its rear end the 25 upper edge is rectilinearly notched as at 30, all for a purpose presently explained. Frame 28 includes an elongated plate 31, that, as next described, serves as a cover for the battery receptacle, and also includes a bail-like part 32, that serves as a handle for the lamp as a whole.

30 For interengagement with the receptacle 11 the cover part 31 along its longitudinal sides has a pair of inwardly curled but open flanges 33 that ride, end-to-end, onto the flanges 29 of the receptacle. The cover slides into engagement with the battery container in the direction indicated by arrow A (FIG. 3) until the cover 31 closes the receptacle 11 as in FIGS. 1 and 9, the frame and can before interengagement being provisionally related as in FIGS. 3 and 6 taken together. Removal 35 of the frame, including the cover 31, for access to the interior of the can to replace the cells is effected by sliding the frame in the opposite direction, as indicated by arrow B (FIG. 1).

Cover plate 31, as best seen in FIGS. 3, 4 and 9, on its underface carries an elongated insulating runner or pad 34 which, in turn, carries metallic contact strips 35 and 36 on its face. The pad is provided with recesses 34b on the top side thereof and contact strips are secured to the pad in this instance by being passed through slots 37 in the pad into recess 34b and the ends 40 bent back onto the body of the pad as at 38. Contact strip 35 is relatively short but of a dimension to make contact with the positive central terminal 12b of the cell 12, while contact strip 36 is long enough to electrically 45 interconnect two of the cells and for this purpose to make contact with both the negative can terminal 13b of the cell 13 and the positive terminal 14b of cell 14. Pushing the frame onto the battery receptacle presses the contacts carried by the cover against the cells and 50 presses the cells against the spring contact tongues in the bottom of the can, already referred to, the forward edge of the pad being sloped, as at 34a, to press the cells downwardly as the cover is slid onto the receptacle.

When the frame is slid onto the receptacle 11 as previously explained, notch or cutout 30 in the rear wall of the receptacle accommodates the insulator member 34 of the cover plate 31 as the latter is slid onto the can and permits the cover and can to make the interengaging connection. The cover plate has a turned down rear lip 55 39 that covers the notch 30 when the frame and can are assembled.

Rivets 40 that hold the insulator runner 34 to the

underside of the cover 31 also clamp thereto the bail-like part 32 of the frame by turned-in ends 41 of the latter which the rivets pass through, the member 32 being substantially wider than it is thick. Bail-like member 32 is bent up along each side of the longitudinal edges of its upper reach 42 to provide a trough 43 which is closed by handle cap 44 that embraces trough 43. Trough 43 and cap 44 together not only form a handle part agreeable to the hand but provide a hollow carrier for the switch terminals 45 and 46 and for the exposed switch actuator or button 47 and its bridge contact means, as next explained.

Terminal members 45 and 46, here shown in the form of metallic rivets carried by the cap 44, are electrically insulated from the latter by headed insulating sleeves 48, respectively, that pass through the cap upper wall 44a under the switch button 47. Terminal rivets 45 and 46 also pass through an insulating plate 49 that is secured to the underside of the cap beneath the switch button 47 by the rivets.

Switch button 47 is shown elongated in the direction of the lamp handle and has a depending boss 50 that enters and plays in a slot 51 that is formed jointly in the upper wall 44a of the cap and in the plate 49 and is located between terminals 45 and 46. Rivets 45 and 46 also clamp to the plate 49 the soldering clips 45a and 46a respectively to which conductors, presently described, are soldered. Secured to the boss 50 by a self-threading screw 52 is a bridging spring contact member 53 elongated similarly to the switch button and slideable with it. Sliding switch button 47 has a thumb rest 47a and is appropriately knurled at 47b.

The front reach of bridge contact 53 has a dent 54 formed therein adapted to resiliently receive the head of rivet 45 and the rear reach is similarly dented as at 55 to receive the head of rivet 46. The front reach of bridge contact 53 is at its extremity flared as at 56 to guide the bridge contact onto the rivet head 45 when the button 47 is slid forwardly, having previously broken contact therewith when button 47 was retracted to the position shown in FIG. 9. Spring tail 57 adjacent socket dent 55 is extended to maintain the bridge contact in engagement with the rivet head 46 at all times. Depression 55 releasably holds the switch button in "off" position and depression 54 in "on" position, thus providing detents for these two positions of the button, the bridge contact 53 being engageable with and releaseable therefrom by its spring character.

Side walls 43 of the handle trough are forwardly extended to form brackets 58 on which are pivoted, on pin 58a, the arms of a clevis 59 that mounts a metallic lamp head 60. Lamp head 60 carries the usual reflector 61 (FIG. 2), lamp bulb 62, glass lens 63, and bezel element 63a, the latter being desirably made of plastic material as is also the switch button 47.

When the parts are assembled as shown in FIGS. 1 and 9 and the switch button 47 is moved forwardly from the position shown in FIG. 9 to the position in which the bridge contact member 53 receives the rivet terminal 45 in its socket depression 54, a circuit is established through insulated wire lead 64 that is soldered to clip 45a at 65 and that extends downwardly along the frame member 32 and is soldered as at 66 to contact 35, through cell 12 to tongue 25 of contact 21, through tongue 24 of the latter to cell 13, through cell 13 to contact strip 36, from contact 36 through cell 14 to tongue 16a of contact 16, from end 16b of the latter through ground 19 to the metal battery container 11, thence through metal frame member 32, clevis 59, metal lamp head 60, through the metal lamp bulb socket (not shown), through the filament of the lamp bulb 62, and through insulated wire lead 67 (that emerges from the lamp head through outlet 60a) to soldering clip 46a, rivet terminal 46, and back to bridge contact 53, whereupon the lamp will be lighted. When the switch button 47 is retracted to the position

shown in FIG. 9, the circuit is broken and the light is extinguished.

The arrangement here described provides a compact and efficient hand lamp, of a practical shape and enhanced utility, ease of insertion of the batteries in the can and closure by the frame being facilitated. When so closed and assembled the switch parts are desirably isolated from the battery can so that fortuitous leakage of the cells, if such should occur, will not injure the switch parts.

10 The invention is not intended to be limited to details of construction shown for purposes of exemplification and it is to be understood that such changes, including modifications or additions, may be made as fall within the scope of the appended claims, without departing 15 therefrom.

What is here claimed is:

1. As an article of manufacture, a multicell operated electric hand lamp comprising an elongated cell receptacle, a plurality of cells arranged in a row in said receptacle, a frame removably mounted on said receptacle, said frame including a cover part for the receptacle having a sliding mechanical and electrical interengaging connection with said receptacle and a bail-like handle structure spanning said cover part, and adapted to support a lamp head at the forward extremity thereof and switch parts including a switch button thereon and electrical contact members carried on the under face of the cover part and insulated therefrom and arranged to make electrical connections with the cells simultaneously with the securing of the cover part to said receptacle by sliding the cover part onto said receptacle.

2. The lamp of claim 1 including an insulating pad in the bottom of the receptacle and wherein vertically resilient electrical contact members are mounted in said pad and vertical dimensions for the accommodation of the cells are such that the cover part is adapted to exert downward pressure upon said cells to insure good electrical connection with the terminals of the cells.

3. In an electric hand lamp, an elongated metallic battery receptacle, a plurality of electric cells of the flashlight battery type arranged in a row in said receptacle, an insulating pad in the bottom of said receptacle, electric contact members carried by said pad and arranged to electrically ground the terminal of an end cell 40 of the row to said receptacle and electrically connect the terminals of the balance of the cells in a part of a series circuit, a frame including a handle for the lamp and a cover for said receptacle, said frame being adapted to support a lamp head and a switch, an insulating pad 45 secured to the underside of said cover, electric contact members carried by said last-mentioned pad and exposed along the bottom surface thereof and engaging the upwardly facing terminals of said cells in said receptacle, said receptacle and said cover having cooperating flanges 50 along the sides thereof for sliding interengagement whereby to mechanically secure said receptacle to said cover and frame and simultaneously make electrical contact and establish series circuit connections with said cells in said receptacle, and a switch lead wire carried by said 55 frame and connected with the contact member which is in engagement with the upwardly facing terminal of the cell remote from the cell having a terminal grounded to said receptacle.

4. Structure in accordance with claim 3 wherein the 60 pad secured to the cover is provided with recesses on the top side thereof facing said cover and the contact members carried by said pad are secured thereto by end portions passing through said pad into said recesses and therein flanged for clamping engagement of said contact members with said pad.

5. Structure in accordance with claim 3 wherein the 65 forward edge of the pad secured to the receptacle cover is sloped to cause said cells within said receptacle to be pressed downwardly as the cover is slid onto the receptacle.

6. Structure in accordance with claim 3 wherein the electric contact member carried by the pad in the bottom of the receptacle and arranged to ground a cell terminal to said receptacle comprises a metallic strip extending slightly beyond an end of said pad, the extended end of said strip abutting the inside surface of said receptacle with pressure engagement to electrically connect said

strip and said receptacle and frictionally latch said pad in position.
